RATTLEPROOF DOOR LATCH

Frank A. Sitko, Fingal, N. Dak.

Application March 28, 1938, Serial No. 198,522

2 Claims. (Cl. 292—163)

This invention relates to rattleproof door latches and has for its principal object to produce a simple yet practical and efficient door latch which will prevent rattling due to gusts of wind against the door and from other causes of vibration.

A particular object of the invention is to provide an improved latch bolt element which will readily snap into engaging relation to the keeper element when the door is closed and having an effective wedging action against the keeper in the closed position of the door and having also a cooperative stop portion for preventing the release of the latch bolt from the keeper element when excess pressure is exerted upon the door tending to force it open.

Another object is to provide an improved rattleproof latch bolt element which may be applied to the ordinary lock body and operating mechanism without material alteration in the latter.

With these and other objects to be attained, as will hereinafter more fully appear, the invention consists in the novel general construction and in the parts and combinations and arrangements of parts as hereinafter described and pointed out with particularity in the appended claims, reference being had to the accompanying drawing, in which

Figure 1 is a fragmentary section through the adjacent portions of a door and door frame, showing the improved latch device applied thereto and the door in closed position; and

Figure 2 is a view partly in elevation and partly in vertical section.

Referring now to the drawing the numeral 10 designates a pillar or jamb member of the door frame having the usual door stop or molding 11 thereon. Secured to the face of the door frame member 10 is a conventional keeper including a striker plate 12 having the camming edge portion 13 and rectangular keeper opening inwardly therefrom and surrounded by a corresponding box-like embossment 14 which is located in a mortise provided therefor in the frame member 10, the corner of the plate and front wall portion 15 of said embossment 14 constituting the keeper or retaining shoulder for the latch bolt as will hereinafter more fully appear.

Set into the adjacent portion of the door 16, in the usual manner, is a latch body housing 17 in which the latch bolt, designated generally by the numeral 18, is slidably mounted as in the ordinary door latch structure, said latch bolt 18 having the usual yoke portion 19 which straddles

the cross-shaft 20 on which the usual door knobs 21 are mounted. As shown, the shaft member 20, which is of square cross-section, has the usual roll-back or cam member 22 sleeved thereon, said member 22 having oppositely extending lugs 23 against which cooperative lugs 24 on the yoke portion 19 are urged by spring members 25 interposed between said lugs 24 and the end portion 26 of the latch body casing 17. The latch mechanism thus far described is of the ordinary construction and arrangement and as far as the present invention is concerned may be modified in many respects, it being understood that the spring elements 25 normally act upon the latch bolt to hold it in extended keeper engaging position and the bolt being retracted by turning the knobs 21 in either direction and causing either of the cam lugs 23 to engage the adjacent lug 24 on the latch bolt so as to force the bolt back against tension of the spring elements 20 25.

The latch bolt 18 has a head 27 which is slidably mounted in the body casing 17 and its forward end portion being projected through the usual front opening provided therefor in the body casing. As shown, the head 27 is provided on one side with a cam face 28 of approximately forty-five degree angularity which engages the camming edge portion 13 of the striker plate as the door is moved into closed position whereby 30 the latch bolt is forced back and rides with its extreme end portion upon the striker plate 12 until the recessed portion 14 is reached, whereupon the latch bolt is snapped into engagement with the corner of the plate 12 and wall portion 15 thereof, as will now be described.

The angularity of the beveled or inclined face portion 28 is such that the latch bolt 18 is readily forced back against the tension of the springs 25 as in the ordinary door latch structure, and 40 the opposite side of the head 27, as shown more clearly in Figure 1, is beveled or inclined, as at 29, at a rather acute angle relative to the longitudinal axis of the bolt as compared to the other beveled portion 28, said face portion 28 being urged into slidable engagement with the adjacent corner portion 30 of the striker plate 12 and wall portion 15 with a wedging action under the force of the springs 25 which moves the door 45 into contact with the stop molding 11.

The wedging action of the latch bolt head portion 27 under the force of the springs 25 is sufficient to prevent rattling of the door under the intermittent pressure of gusts of wind and from other causes of vibration and will ordinarily 55

- hold the door closed under such conditions, but, to prevent the door from being forced open when subjected to considerable excess pressure or vibratory force a longitudinal off-set shoulder portion 31 is provided at the extreme end of the latch bolt in marginal merger with the two beveled or inclined faces 28 and 29. This off-set shoulder portion 31 will engage the wall portion 15 of the keeper adjacent the corner 30 if the latch bolt 18 is forced back by the engagement of the inclined portion 29 on the corner portion 30 of the keeper when excessive force is applied to the outer side of the door 16 and thereby effectively holds the door against opening except for a very slight distance away from the stop molding 11, thus functioning as a safety catch to prevent the opening of the door unless the latch bolt 18 is retracted by manipulation of the knobs 21.
- 20 In accordance with the present invention, provision is made for a definite normal projection of the head portion 27 of the latch bolt beyond the edge of the door so as to take care of the variation in the space between the edge of the door and the adjacent side of the pillar or jamb member 10 due to swelling and shrinkage because of the change in atmospheric conditions, that is to say, the lug portions 24 are located on the yoke 19 of the latch bolt so as to engage the opposed lugs 23 on the roll-back 22 when the latch bolt is at the limit of the longest relative projection of its head portion 27 but are spaced an appreciable distance from said lugs 23 when the beveled portion 29 of the head 27 engages the corner 30 of the keeper in the closed position of the door under normal atmospheric conditions.
- Obviously, the structure admits of considerable modification within the spirit and scope of the invention as defined by the appended claims. The invention, therefore, is not limited to the specific construction and arrangements shown.
- What is claimed is:
1. In a door latch, in combination with a conventional keeper having a retaining shoulder opposed to the conventional stop against which the door is closed, a spring-pressed latch bolt having a head portion normally projected in keeper-engaging position, the projected head portion of the bolt formed with an inclined end face of substantial length on one side of a longitudinal plane with its forward end terminating in such plane, said inclined face being of camming angularity to engage the keeper and force the bolt back during the closing of the door but

being free of engagement with the keeper when the door is closed, an opposed inclined end face also of substantial length on the head portion of the bolt relatively inward from the other inclined face and with its forward end terminating in the same longitudinal plane, said opposed inclined face being of more acute wedging angularity to engage the retaining shoulder of the keeper and hold the door in its closed position against the door stop, and a flat longitudinal stop shoulder on the head portion of the bolt of lesser length than each of said inclined faces and extending between the ends of the two faces in the plane thereof to engage the retaining shoulder of the keeper and hold the door substantially closed upon partial retraction of the bolt and disengagement of said opposed inclined face of the bolthead from the keeper shoulder.

2. In a door latch, in combination with a conventional keeper having a retaining shoulder opposed to the conventional stop against which the door is closed, a spring-pressed latch bolt having a head enlargement of polygonal form at its outer end normally projected in keeper-engaging position, said head having flat guide faces on opposite sides thereof, an inclined end face of substantial length extending from one guide face and terminating at its forward end in a plane parallel and adjacent to the longitudinal axis of the bolt, the angularity of said inclined face being approximately forty-five degrees from said guide face and engaging the keeper with cam effect to force the bolt back during the closing of the door but being free of engagement with the keeper when the door is closed, an opposed inclined end face, also of substantial length, extending from the opposite guide face of the bolthead at an angle of substantially thirty degrees and terminating with its forward end in the same plane with but at a relatively short distance inwardly from the end of the other inclined face, said opposed inclined face wedgingly engaging the retaining shoulder of the keeper and holding the door in its closed position against the door stop, and the bolthead being formed with a flat longitudinal stop shoulder in the plane between the forward ends of the two inclined end faces to engage the retaining shoulder of the keeper and hold the door substantially closed upon partial retraction of the bolt and disengagement of said opposed inclined face of the bolthead from the keeper shoulder.
